UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,346, dated May 22, 1888.

Application filed April 20, 1888. Serial No. 271,350. Term of patent 3½ years.

To all whom it may concern:

Be it known that I, JENNIE SHEILS, of the city, county, and State of New York, have invented and produced a new and original Design 5 for a Pattern of a Lady's Costume; and I do hereby declare that the engraved prints accompanying this specification convey to any one accustomed to using paper patterns a clear understanding of how a garment made up by 10 the pattern will appear.

The design shows a polonaise and a round walking-skirt. The skirt displays a flat drapery passing entirely around it and falling in plaits at either side of the front and in loose 15 folds at the back. The polonaise displays close-fitting fronts closing in a curve from the top of the right shoulder to the left hip, the right front forming a long oval tablier that

hangs nearly to the edge of the skirt and displays draping plaits in its side edges; long 20 pointed panels descending from the hips nearly to the edge of the skirt; a close-fitting back exhibiting underfolded plaits at the end of the center seam; a long loose loop at either side and loopings at the center and falling in a long 25 oval outline, coat-sleeves, and a standing collar.

What I claim as my invention, and desire to secure by Letters Patent, is—

The design for a lady's costume, as shown 30 in the engraved prints accompanying this specification.

JENNIE SHEILS.
